US00D604343S

(12) **United States Design Patent**
Murakami et al.

(10) **Patent No.:** US D604,343 S
(45) **Date of Patent:** ** Nov. 17, 2009

(54) **SAMPLE CRUSHING AND PULVERIZING APPARATUS**

(75) Inventors: **Seigo Murakami**, Tokyo (JP); **Nobuyuki Nakagawa**, Tokyo (JP); **Koichi Osawa**, Tokyo (JP); **Akira Ishii**, Tokyo (JP)

(73) Assignees: **Hirata Corporation** (JP); **Bio Medical Science, Inc.** (JP)

(**) Term: **14 Years**

(21) Appl. No.: **29/311,663**

(22) Filed: **May 20, 2009**

(57) **CLAIM**

The ornamental design for a sample crushing and pulverizing apparatus, as shown and described.

DESCRIPTION

FIG. 1 is a front perspective view of the sample crushing and pulverizing apparatus;

FIG. 2 is a front view thereof;

FIG. 3 is a plan view thereof;

FIG. 4 is a side view thereof;

FIG. 5 is a rear view thereof;

FIG. 6 is a bottom view thereof; and,

FIG. 7 is a perspective view of the sample crushing and pulverizing apparatus of FIG. 1 in an opened state.

The broken lines in the drawings depict unclaimed environmental subject matter.
